UNITED STATES PATENT OFFICE.

ERNEST WILLIAM CARLETON AND JAMES MADISON ODELL, OF AUSTIN,
TEXAS.

REFRIGERATING APPARATUS.

SPECIFICATION forming part of Letters Patent No. 527,831, dated October 23, 1894.

Application filed August 25, 1893. Serial No. 484,035. (No model.)

To all whom it may concern:

Be it known that we, ERNEST WILLIAM CARLETON and JAMES MADISON ODELL, of Austin, in the county of Travis and State of Texas, have invented a new and Improved Refrigerating Apparatus, of which the following is a full, clear, and exact description:

Our invention relates to an improvement in refrigerating apparatus, and it has for its object to provide an economic and durable receptacle in which to keep and preserve meat, butter, eggs, milk, vegetables, fruit, &c., cool and in good condition in warm weather without the use of ice or of chemicals.

15 A further object of the invention is to provide a simple and effective means for reducing the temperature of the air in a partially closed chamber by the evaporation of water brought about through the medium of capillary attraction, and likewise to provide for automatically maintaining a predetermined level of water in the water chamber of the apparatus, and a thorough ventilation of the refrigerating chamber thereof.

20 The invention consists in the novel construction and combination of the several parts, as will be hereinafter fully set forth and pointed out in the claims.

Reference is to be had to the accompanying drawings, forming a part of this specification, in which similar figures and letters of reference indicate corresponding parts in all the views.

Figure 1 is a side elevation of the apparatus, portions being broken away. Fig. 2 is a horizontal section taken practically on the line 2—2 of Fig. 1; and Fig. 3 is a vertical section taken essentially on the line 3—3 of Fig. 1.

25 The apparatus may be said to consist primarily of a base A and a body B in which the refrigerating chamber is located, a tank section C, and a cap section D. The base section of the apparatus is preferably made oblong with rounding ends, and consists of a bottom board or plate 10 and a metallic band 11, secured to the base, extending both above and below it, and a metal floor 12, of zinc or galvanized iron, extending over the top of the bottom board or plate 10. The floor 12, has erected upon it an oval upright flange 13,

placed a predetermined distance from the upper edge of the band 11, forming thereby a marginal channel 14. Legs 15, are employed at the end portions of the base to support the same, and the base is further provided with a water-receiving pan 16, which is in the nature of a drawer, and is adapted to slide in suitable guide ways produced in the under portion of the base.

30 An aperture 17, is made in the floor 12 and bottom 10 of the base, leading directly into the water pan 16; and an overflow pipe 18, is located at a predetermined point in the channel 14 of the base, said overflow pipe extending above the floor 12 of the base a predetermined distance, its lower end being in communication with the water pan 16, as shown in Fig. 3.

The body B of the apparatus is of like form 35 as the base, and the lower end of the bottom of the body is adapted to rest upon the floor of the base within the channel 14. The body consists of a frame comprising an upper and a lower oval band or ring, designated respectively as 19 and 20, which bands or rings are preferably galvanized, and are connected by series of upright rods 21, which are likewise galvanized. A coarse wire netting 22, preferably galvanized, is secured to the frame in 40 any suitable or approved manner, and extends entirely around the same, since the body is open at its top and at its bottom. A roll of from five to seven thicknesses of linen or cotton netting, similar to coarse mosquito 45 bar, or like material 23, is wrapped entirely around the inner netting 22, and the fabric covering of the body is in its turn covered entirely by a jacket or wrapper of a fine wire netting 24, which may be galvanized or may 50 be made of aluminum. The fine wire netting, and likewise the inner coarse netting 22 may be substituted by perforated plates, if found desirable.

An opening is made in one portion of the 55 body, preferably its front, which opening is normally closed by a door 25, and this door is usually provided with a glass or a transparent panel in order that the interior of the body may be rendered visible, and through 60 the medium of the door accessible, since the interior of the body is adapted to constitute

a refrigerating chamber of which the floor 12 of the base will be the bottom.

As heretofore stated, the body is made to rest upon the floor of the base within the channel 14, and the covering of the body is cut away, as shown in Fig. 3, at one point to sufficiently clear the upper end of the overflow pipe 18.

The tank section C of the apparatus, consists as its name implies, of a tank 26, also of oval contour, which is open at the top and provided with a bottom arched upon its under surface. The tank is of less dimensions than the dimensions of the body, as it is intended to extend partially within the body at the top, and provide a space between its outer surface and the inner surface of the body, as shown best in Figs. 1 and 3. To that end the tank is provided with brackets 27 upon its sides and ends, which brackets rest upon the upper ring or band of the body, as is best shown in Fig. 3. A false bottom or shield 28, is suspended beneath the bottom of the tank, the false bottom or shield being of like shape as the true bottom of the tank, and the said false bottom is adapted to receive any water of condensation that may form upon the bottom of the tank, and cause it to drop down into the channel 14 so that articles placed on the bottom 12 will not be moistened by such condensation water. Tubular standards 29, preferably two in number, are secured to the bottom of the tank, one at each side of the center, the standards passing through the bottom and extending above the top of the tank. By this means a circulation of air is obtained at all times through the refrigerating chamber. The tubular standards are adapted as supports for water reservoirs 30, said water reservoirs being preferably of circular shape and provided with an inner tube 31, extending through them from top to bottom, and beyond the top, the tube of the reservoirs being slipped over the tubular standards; and the reservoirs are adapted to have sliding movement upon the standards, being held at any desired point in the length of the latter through the medium of set screws 32, which are passed through the upper ends of the reservoir tubes to an engagement with the standards. Each reservoir is provided with a valved inlet 33, through the medium of which it is filled, the inlet being located at the top; and an outlet 34, is produced in each reservoir at the bottom, which may be closed when desired by a stopper 35, connected with the body of the reservoir by a chain 36. Each reservoir is also ordinarily partially surrounded by a curved partition or guard 37, secured to the bottom of the tank, for a purpose to be stated hereinafter.

A force pump 38, is located preferably upon one outer side of the tank, and the said pump is provided with a tube 39, which is adapted to be placed in the tank, and a second pipe 40, which extends downward through the refrigerating chamber and through the open-

ing 17 in the bottom thereof into the water pan 16.

In connection with the tank a rack E, is employed. This rack is of greater dimensions than the tank, and practically of about the same dimensions as the body. The rack consists of two or more oblong rings or bands 41 and 42, preferably made of stout wire or bar metal, the rings or bands being placed concentric one above the other and connected by cross or tie rods 43, the cross or tie rods being formed at their lower ends with inwardly-extending hooks 44, or the equivalents thereof; and the rack is placed over the tank, its hooks resting upon the upper edges thereof. This rack is adapted to be covered with preferably continuous strips of woolen material, such as flannel; designated in the drawings as 45, of one or more thicknesses, covered with or attached to one or more thicknesses of cotton or linen cloth 46, or a cloth known as cheese-cloth, the absorbent material, namely, the cloth and flannel, being so placed upon the rack that when the rack is placed upon the tank the absorbent material will extend down into the tank near its bottom, and about the same distance outside of the tank, and when so placed the outer portion of the absorbent material will engage with or touch the absorbent material covering the body.

The apparatus is covered by a cap D, which is supported on the guards 37 so as to be out of contact with the absorbent material 46, and extends down a predetermined distance over the outer side of the body, being spaced therefrom as shown in both Figs. 1 and 3, and the cap is provided with openings 47, through which the reservoirs may pass outward and upward, and with a central opening 48, covered by a door 49, through which opening the depth of water in the tank may be observed.

The reservoirs 30, are adapted to automatically regulate the amount of water in the tank, preserving the level of the water, which is accomplished in the following manner: The tank having been nearly filled with water, and the reservoirs likewise filled, the valves in the inlets of the reservoirs are closed, and the reservoirs are lowered to a point in the tank denoting the level of the water to be preserved. The reservoirs are then fixed upon their standards and their stoppers are withdrawn. The water will not flow from the reservoirs as long as the water in the tank covers their outlet openings, since air can not enter the reservoirs at the top; but the moment that the water in the tank falls below the predetermined level, the water in the reservoirs will escape and restore the desired level, and will then stop running.

The atmosphere within the refrigerating chamber is maintained at a low temperature by the absorbent material taking up the water from the tank and communicating it to the absorbent material surrounding the re-

frigerating chamber. In fact, the process will be as follows: The water coming in contact with the flannel or cloth 45, by capillary attraction will be drawn up said cloth from the tank, and by the same attraction fed to the cheese-cloth or cotton fabric 46, and from this fabric to the netting where it will be dispensed over the entire wrapping of that material, and likewise over the fine wire, remaining there until the moisture is exhausted by evaporation. The surplus of water dripping from the wrapping of the body will be received in the channel of the base, and at all times there will be a certain amount of water in the channel, the depth being regulated by the height of the overflow pipe 18. Consequently the lower edge of the body wrapping will be always damp. The surplus of water in the base channel will flow through the overflow 18 into the water pan 16 in the base. When it is desired, by manipulating the pump 38, the water may be drawn from the base water pan and delivered again to the upper tank.

25 By means of the foregoing construction a cool atmosphere is created inside of the refrigerating chamber. At the same time the chamber is thoroughly ventilated, since pure air is constantly passing through it in every direction and the air is free to circulate in the space between the tank 26 and the chamber or body B. It may here be remarked that the warmer the weather the greater difference in temperature there will be between the air inside and that outside of the refrigerating chamber.

Having thus described our invention, we claim as new and desire to secure by Letters Patent—

40 1. In a refrigerating apparatus, a refrigerating chamber the walls of which are composed of a loosely woven fabric capable of absorbing and retaining moisture, and an inner and outer binding wall of metal network, each in contact with the said fabric substantially as described.

45 2. In a refrigerating apparatus, a refrigerating chamber, the walls of which are composed of material capable of absorbing and retaining moisture, and a binding material of netted construction, a tank adapted to contain water located above and extending partially in the refrigerating chamber, a space intervening between the walls of the chamber and those of the tank, an absorbent material supported by the tank, extending in the same and out to an engagement with the corresponding material in the body of the refrigerating chamber, whereby water is conveyed from the tank to the walls of the refrigerating chamber by capillary attraction, and a cap covering the upper portion of the refrigerating chamber and tank, and means, substantially as shown and described, for disposing of the surplus water, as specified.

50 3. In a refrigerating apparatus, a refriger-

ating chamber having its walls composed of a moisture absorbent and moisture retaining material, a binding material holding the absorbent material in place, and a tank adapted to contain water, located partially within the chamber, a space intervening between the walls of the tank and the walls of the chamber, an absorbent material connecting the interior of the tank with the corresponding material of the refrigerating chamber, whereby through capillary attraction the walls of the chamber will be kept moist, and the temperature of the air within the refrigerating chamber will be lowered by the constant evaporation of water from its walls, as and for the purpose specified.

4. In a refrigerating apparatus, a refrigerating chamber having its walls composed largely of a moisture retaining material, a tank located within a portion of the chamber and adapted to contain water, an absorbent material adapted to receive water by capillary attraction, connecting the interior of the tank with the walls of the refrigerating chamber, and water reservoirs adjustably located in the tank, adapted to preserve a predetermined level of water in the tank, substantially as and for the purpose set forth.

5. In a refrigerating apparatus, the combination, with a base having a channel upon its upper face, an overflow pipe leading from the channel, and a water-receiving tank connected with the overflow pipe, of a refrigerating chamber, the wall of which is largely composed of a moisture-absorbing material, the lower end of the chamber and the material of its walls being fitted in the channel of the base, a water tank located in the upper portion of the chamber, provided with tubular standards extending through from top to bottom, a water absorbent material held in suspension over the tank, communicating with its interior and with the walls of the refrigerating chamber, a cover for the tank and chamber, and means, substantially as shown and described, for supplying water to the tank, as and for the purpose set forth.

6. In a refrigerating apparatus, the combination, with the refrigerating chamber the walls whereof are composed of a moisture absorbing and moisture retaining material, of a tank located adjacent to the said chamber, an absorbent material connecting the interior of the tank with the walls of the refrigerating chamber to continuously supply them with moisture, standards extending within the tank, and water reservoirs that are adjustable longitudinally of the standards, and constructed to preserve a predetermined level of water in the tank, substantially as described.

7. In a refrigerating apparatus, a refrigerating chamber the walls of which are largely composed of a moisture absorbing and retaining material, a water tank suspended in the upper portion of the chamber, provided with tubular standards extending from top to bot-

tom, a rack located over the tank, an absorbent material carried by the rack, which conveys the water from the tank to the walls of the chamber, and a cap fitted loosely around the 5 chamber and over the tank and rack, substantially as shown and described, whereby the interior of the chamber is kept cool by

means of moisture, and a perfect circulation of air in the chamber is obtained, as specified.
